TENSION DEVICE

Application filed March 12, 1929. Serial No. 346,477.

This invention relates to mechanism for automatically controlling the tension on sheet material as it is being drawn from a roll. In the many instances where paper or other sheet material is operated on by automatic machinery, the material is usually supplied in rolls which are made as large as practicable to minimize the frequency of renewals of the supply. In order to avoid breakage of the material from excess tension and to deliver the material at a uniform tension provision must be made to counteract various disturbing factors such as the varying diameter of the supply roll which decreases as the material is taken therefrom, and frictional variations in the bearings which support the roll. It is an object of the invention to provide a tension mechanism which is relatively simple, is sensitive to small changes in the tension of the sheet and which acts promptly and automatically to check incipient variations in tension. The invention is particularly applicable to machines for operating on paper supplied from successive rolls of paper which may be mounted on a plurality of spindles carried by a rotary frame and swung into place one after the other. By my invention each roll-carrying spindle may be provided with its own tensioning device controllable by mechanism responsive to tension on the paper in the machine itself just as it is about to be operated on. As each roll is moved into feeding position, the tensioning mechanism of its spindle automatically comes into operative relation with the controlling mechanism without requiring any action on the part of an operator to connect these mechanisms or to adjust the connection. Other advantageous features will be apparent to one skilled in the art from the disclosure of the invention in the description which follows and the drawings, of which,—

Figure 1 is a side elevation of mechanism embodying the invention.

Figure 2 is a plan view of the same.

Figure 3 is an elevation of a multiple spindle support for rolls of sheet material.

Figure 4 is a fragmentary side elevation of ratchet mechanism employed in the apparatus.

Figure 5 is an end elevation of the same.

Figure 6 is a perspective view of a pair of pawls used in the apparatus.

Figure 7 is a fragmentary view of a cam member cooperating with the elements shown in Figure 6.

Referring to the drawings in detail, a machine for operating on a strip of paper or the like may be suitably positioned to draw a strip of sheet material from a supply roll mounted on a suitable standard adjacent thereto. As shown in Figures 1 and 2 a portion of the framework of such a machine is indicated at 10. Spaced therefrom may be a standard 11 rising from a suitable base 12, the standard 11 pivotally supporting a number of arms 13 which may be arranged in the form of a star wheel, as shown in Figure 3. Each of the arms 13 supports a spindle 14 capable of rotatably carrying a roll 15 of paper or other sheet material which is to be fed to the machine 10. For successful operation of most machines which operate on a paper strip, it is important that the strip be supplied thereto under a relatively uniform tension. In order to regulate the tension automatically as it enters the machine 10, each spindle 14 may be supplied with suitable retarding means which may include a brake drum 16 having a brake band 17 engaging a portion of its peripheral surface. One end of the brake band 17 may be adjustably anchored as at 18, a wing nut 19 or threaded hand wheel being supplied to facilitate manual adjustment of the minimum tension on the brake band 17. As shown in Figure 1, the other end of the brake band may be secured to the periphery of a take-up drum 20, this drum being fixed to a rock-shaft 21 having a crank arm 22 secured thereto.

A pitman 23 may be pivotally connected to the crank arm 22, the pitman being suitably guided as by a member 24 bolted through spacing lugs to the arm 13. These parts are so arranged, as shown in Figure 1, that axial thrust on the outwardly projecting end of the pitman 23 will rock the shaft 21 so as to increase the tension on the brake band 17 and thus to increase the retarding effect.

on the spindle 14. In order to actuate the pitman associated with the spindle which is in position for sheet feeding, I may provide an upright bar 25 which may be conveniently hinged as at 26 to the floor or any suitable support. A push rod 27 may be pivotally connected to the bar 25 at a suitable height, depending on the height of the machine frame 10. As each spindle 14 with its roll 15 swings into feeding position, its projecting pitman 23 comes into operative contact with a face of the bar 25 so that a thrust through the push rod 27 which results in rocking the bar 25 on its pivot 26 causes a thrust on the pitman 23 which, in turn, varies the braking effect on the spindle 14 from which the sheet is being fed.

Suitable mechanism for automatically regulating the axial thrust on the rod 27 may be mounted on the machine frame 10, as illustrated in Figures 1 and 2. This mechanism may comprise a rack 28 secured to or formed on the rod 27, this rack being meshed with a pinion 29. The pinion 29 may be mounted on a suitable shaft 30 on which is also mounted a ratchet wheel 31 the teeth of which are engageable by one of a pair of pawls 32, 33. These pawls are normally held out of operative relation with the teeth of the ratchet wheel 31 by a sector-shaped member 34 having a pair of auxiliary offset arcuate edges 35, 36 concentric with the shaft 30 and rockable about the shaft as an axis. On these edges respectively ride teeth 320 and 330 of the pawls 32, 33. The tooth 330 is offset from the tooth 320 so as to clear the cam 35. This tooth extends over laterally to have a portion engageable with the ratchet wheel 31. A similar extension 321 is provided with the tooth 320, but spaced therefrom to provide clearance for the cam 36. A pair of flat springs 300 may be employed to keep the teeth 320 and 330 pressed respectively against the cams 35 and 36. During the operation of the machine which operates on the sheet material, the pawls 32 and 33 are constantly reciprocated vertically. For this purpose, they may be mounted upon a common supporting rod 37 which is reciprocated as by an eccentric 38 carried by a suitable gear 39 driven by a pinion 40 mounted on a driven feed roll 41 which assists in feeding the sheet to the machine 10. The sheet is preferably passed over the feed roll 41 in contact with a sufficient portion of the periphery thereof to provide a desired amount of traction between the roll and the sheet, and at the same time to permit slippage to relieve differences of tension on the portions of the sheet approaching and leaving the feed roll, the surface of the roll being sufficiently smooth for this purpose.

As the pawls reciprocate vertically their teeth 320 and 330 ride off the edges of the respective surfaces 35 and 36, so that the teeth

321 and 330 of the pawls are successively in position to engage a tooth of the ratchet wheel 31, but the stroke of the rod is not sufficient to result in an actual movement of the wheel 31 while the member 34 is in the position illustrated in Figure 4. If, however, the member 34 is rocked in one direction or the other about the shaft 30, this permits one of the pawls to drop behind a tooth of the ratchet wheel 31 so that the wheel is rotated through a slight angle during the remainder of the stroke of the pawl. This results in a small axial movement of the push rod 27 which, in turn, increases or decreases the tension on the brake band 17, and hence the tension on the sheet which is being fed from the roll 15. The position of the member 34 may be governed by suitable connections with a roll 42 which rides on a stretch of the sheet material between the feed roll 41 and the operating elements of the machine 10. Thus the tensioning mechanism is responsive to the tension of the sheet as it actually reaches the operating mechanism.

As shown in Figures 1 and 2, the roll 42 may depend from a pair of rock arms 43, 44 by suitable links 45, the upper ends of the links being connected together as by a cross bar 46 to maintain the roll 42 horizontal. A suitable weight may be mounted on the cross bar 46 to adjust the pressure of the roll 42 on the sheet of material passing thereunder. A centrally pivoted rock arm 47 abuts at one end a lug on one of the links 45, its other end being attached as by a ball and socket joint to a second centrally pivoted rock arm 48, the latter being pivotally connected at its other end to an extension 49 of the member 34. Through this linkage, any rise or fall of the roll 42 will result in a rocking movement of the member 34. Hence a slackening of the tension of the sheet passing under the roll 42 will result in a lowering of this roll, and a rocking of the member 34 which will permit the pawl 32 to engage one of the teeth of the ratchet wheel 31 so as to rotate this wheel through a small angle. This results in axial motion of the push rod 27 toward the right which increases the tension on the brake band 17 and hence increases the tension on the sheet from the roll 15. This slight increase of tension is increased by the engagement of the pawl 32 with successive teeth of the ratchet wheel 31 until the tension of the sheet is sufficiently increased to raise the roll 42 to its normal position, whereupon the member 34 resumes its neutral position as shown in Figure 4. A greater than normal tension on the sheet will raise the roll 42, thus rocking the member 34 so as to permit the pawl 33 to engage successive teeth of the ratchet wheel 31 and thereby to diminish the tension on the brake band 17 and hence on the sheet. In order to obviate unnecessary operation of the controlling mechanism due

to momentary fluctuations in the tension of the sheet such as, for example, might be caused by an eccentric winding of the roll 15, I may provide a dash-pot 50 which may be connected to the rock arm 43 so as to prevent any violent oscillation of the roll 42. The dash-pot 50 may be of any suitable construction, devices of this kind being well known in the art.

In operating the mechanism shown, each 10 spindle may be supplied with a full roll of paper or other sheet material as it reaches the loading station. After each roll 15 is unwound the arms 13 may rotate so as to bring the next spindle with a full roll into feeding position, the spindle which is moved from feeding position being supplied with a fresh roll of material so as to be ready to resume feeding position in its turn. As each 15 roll is swung into feeding position the pitman 20 23 of its tensioning mechanism automatically engages the bar 25. If the tension on the sheet as it starts feeding is not as desired, the automatic mechanism quickly varies the tension to the proper magnitude, after which 25 it is kept thereat automatically as hereinbefore described.

Having thus described an embodiment of this invention, it should be evident to those skilled in the art that various changes and modifications might be made therein without departing from its spirit or scope as defined by the appended claims.

I claim:

1. Mechanism of the class described comprising a rotatable spindle for a roll of sheet material, means for retarding the rotation of said spindle, power means for adjusting said retarding means, including a rack operatively connected with said retarding means and a pair of opposed pawls adapted to engage said rack for movement thereof to adjust said retarding means, and means responsive to the tension on the sheet material at a point remote from the roll for controlling the operation of said power means, said controlling means including a cam member normally holding both said pawls out of operative engagement with said rack, said cam 50 member being movable in response to variations of sheet tension to permit engagement of one pawl or the other with said rack.

2. Mechanism of the class described comprising a rotatable spindle for a roll of sheet material, a brake-drum thereon, a brake-band engaging a portion of the periphery of said drum, adjustable anchoring means for one end of said band, a rotatably mounted take-up drum secured to the other end of said band, a crank-arm for rotating said take-up drum, a rod pivotally connected to said crank-arm and axially movable to tension said brake-band, and means controlled by the tension of the sheet material from the roll for

moving said rod to regulate the brake-band tension.

3. Mechanism of the class described comprising a spindle for a roll of sheet material, a frame supporting said spindle and actuatable to move said spindle into and out of sheet-feeding position, sheet tensioning means carried by said frame, reversible power means for actuating said tensioning means, and means directly responsive to changes of tension in the sheet for controlling the operation of said actuating means, said tensioning means being arranged to automatically move into operative relation with said actuating means when said spindle is moved into sheet-feeding position and to move out of operative relation with said actuating means when said spindle is moved out of sheet-feeding position.

4. Mechanism of the class described comprising a spindle for a roll of sheet material, a frame supporting said spindle and actuatable to move the spindle into and out of sheet-feeding position, a brake drum on said spindle, means frictionally engaging said drum to retard rotation of said spindle, and power driven means for adjusting the frictional drag on said drum, said power driven means including mechanism carried by said frame and movable with said spindle and other mechanism operatively engageable by said movable mechanism when the spindle moves into sheet-feeding position.

5. Mechanism of the class described comprising a spindle for a roll of sheet material, a frame supporting said spindle and actuatable to move said spindle into and out of sheet-feeding position, means carried by said frame for retarding the rotation of said spindle, and means for actuating said retarding means in response to variations in the tension on the sheet fed from the roll, said actuating means including a reciprocable member presenting a face toward said frame, said retarding means having an element movable into operative engagement with said face when said spindle moves into sheet-feeding position.

In testimony whereof I have affixed my signature.

HOWARD PARKER.
